(57) **CLAIM**

The ornamental design for a refractory anchor, as shown and described.

DESCRIPTION

FIG. 1 is a perspective view of a refractory anchor according to the present invention.

FIG. 2 is a front elevation view of the refractory anchor of FIG. 1, the rear elevation view being identical.

FIG. 3 is a left side elevation view of the refractory anchor of FIG. 1, the right side elevation view being identical.

FIG. 4 is a top plan view of the refractory anchor of FIG. 1; and,

FIG. 5 is a bottom plan view of the refractory anchor of FIG. 1.

The broken lines in the drawings illustrate portions of the refractory anchor and form no part of the claimed design.

1 Claim, 3 Drawing Sheets
